(57) CLAIM

The ornamental design for the remote control, as shown and described.

DESCRIPTION

FIG. 1 is a perspective view of a first embodiment of a remote control showing our new design;

FIG. 2 is a top plan view thereof;

FIG. 3 is a bottom plan view thereof;

FIG. 4 is a left side elevational view thereof, the right side elevational view being a mirror image thereof;

FIG. 5 is a rear elevational view thereof; and,

FIG. 6 is a front elevational view thereof.

The broken lines are for illustration purposes only and form no part of the claimed invention.
